(57) **CLAIM**

We claim the ornamental design for a display screen with graphical user interface for analyzer, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen with graphical user interface for analyzer showing the claimed design in accordance with one embodiment.

FIG. 2 is a front view of a display screen with graphical user interface for analyzer showing the claimed design in accordance with another embodiment; and,

FIG. 3 is a front view of a display screen with graphical user interface for analyzer showing the claimed design in accordance with another embodiment.

The broken line showing of a device and a display screen with graphical user interface is included for the purpose of showing portions of the article which form no part of the claimed design.
